UNITED STATES PATENT OFFICE.

CLARENCE B. HODGES, OF DETROIT, MICHIGAN, ASSIGNOR TO DETROIT LUBRICATOR COMPANY, OF DETROIT, MICHIGAN, A CORPORATION OF MICHIGAN.

FORCE-FEED LUBRICATOR.

No. 893,241.

Specification of Letters Patent. Patented July 14, 1908.

Application filed February 11, 1907. Serial No. 356,904.

To all whom it may concern:

Be it known that I, CLARENCE B. HODGES, a citizen of the United States of America, residing at Detroit, in the county of Wayne and State of Michigan, have invented certain new and useful Improvements in Force-Feed Lubricators, of which the following is a specification, reference being had therein to the accompanying drawings.

10 The invention relates to new and useful improvements in force feed lubricators, and consists particularly in the construction of a lubricator having a force feed or pump which takes the oil from the reservoir and delivers it through a "bleeder" or sight feed, returning to the reservoir, and either the same pump or another one which takes a similar quantity of oil from the reservoir and delivers it to the point to be lubricated, all as 15 more fully hereinafter described and particularly pointed out in the claims.

In the drawings, Figure 1 is a vertical section through a reservoir containing two pairs of pumps, one of which is in section and one 20 in elevation, and embodying my invention; Fig. 2 is a vertical section through one of the pumps and the reservoir shown in Fig. 1; Fig. 3 is a horizontal section on line 3—3 of Fig. 2; Fig. 4 is a vertical section through 25 the lower end of the valve casing, pump and connections, showing the construction of the pump which takes the oil from the reservoir and delivers it to the part to be lubricated; Fig. 5 is a section similar to Fig. 1, showing 30 a modified form of the pump, with suitable valves, which in one reciprocation delivers the oil through a "bleeder" or sight feed and back to the reservoir, and in the next reciprocation takes the oil from the reservoir and 35 delivers it to the point to be lubricated; Fig. 6 is a horizontal section on line 6—6 of Fig. 5; Fig. 7 is a vertical section on line 7—7 of Fig. 6; Fig. 8 is a section on line 8—8 of Fig. 6.

A indicates a reservoir, in which in this 40 case I have located the pump and the pumping apparatus.

B and B' indicate two cylinders within the pump, and I have shown these cylinders as cast integral with the valve casing C, in which 45 is a rotary shaft, D, which acts as a valve by means of the ports a therein. The valve shaft D has on its end the worm wheel E, which engages with a worm F driven from any suitable source of power. On the opposite 50 site end portions of the shaft D are cam

wheels G, which are rotated with the valve shaft and which have camways with which engage the pins or roller wrists b on the yoke H, which are connected to the rods I and which at the top are connected by the cross head I'.

J J' indicate two pistons connected together in pairs by the connecting bar K. To this connecting bar, and in the construction I have shown centrally thereof, is connected the adjusting stem L, one for each pair of pump pistons. These stems are connected to the cross bar in such a way that they may be rotated therein. These stems are provided with a screw-threaded portion c, and preferably extend through the top of the casting. This screw threaded portion engages a nut d within said cross bar or horizontal portion, there being preferably a flange e to prevent the nut from rotating when the adjusting stem is turned. Below the crossbar the adjusting stem is provided with a pin, stop or shoulder h, the construction being such that by rotating the stem L the distance between pin, shoulder or stop h and the nut d will be varied, and consequently the throw or movement of the pistons J J' will be correspondingly varied. It is obvious from this description that adjustment of a single stem L will correspondingly adjust the throw or travel of both of the pair of pistons, and therefore that each piston when adjusted will pump the same amount of oil.

One of the pumps (in this case I have shown it as the pump J') has the inlet conduit M and the discharge conduit M', the discharge conduit leading in this case through the top of the casing of the reservoir and having a discharge nozzle i, which discharges back through a nipple k in the top of the tank or reservoir. I may let this nozzle simply discharge through the air without any inclosing sight-feed glass, in which case it is commonly called the "bleed," or I may surround it with a sight-feed glass l, so as to prevent the oil from getting on the exterior of the reservoir. The other pump of each pair has an inlet induction conduit N, and an outlet pipe N', which leads to the point to be lubricated. The rotary valve, with its ports a, is constructed and rotated so that each pump will be respectively connected with the inlet and discharge at the proper time, withdrawing the oil and discharging it at each revolution. It will be seen that with this

construction, each pair of pumps being adjusted to give a uniform feed or travel, one pump will discharge a quantity of oil from the reservoir and back thereto and through 5 its "bleed" or sight-feed, thus advising the operator, upon inspection, of the amount of oil being fed at each reciprocation; while the other pump, pumping a similar quantity will draw the oil from the reservoir and dis- 10 charge it directly to the point to be lubri- cated. It is obvious, of course, that there is a separate adjustment for each pump, such as J^2 .

With the construction shown in Figs. 5, 6, 7 15 and 8 I have shown this same result obtained by a slightly modified form of apparatus,— that is, by having a single pump which alternately pumps to the sight-feed or "bleed" and to the point to be lubricated.

20 The construction of cylinder, valve casing, rotary valve, cams, crosshead and actuating devices is exactly the same as described for the construction shown in Figs. 1, 2, 3 and 4, excepting that the pumps are not connected 25 up in pairs, but each pump has its own independent adjustment between it and the crosshead. The valve shaft or rotary valve is provided with two ports or notches m and m' , arranged side by side and both commu- 30 nicating with a single cylinder. The port m is adapted to connect the pump with the inlet port P leading to the bottom of the reservoir and with the outlet port P' , which leads to the sight-feed nozzle or "bleed" i , 35 while the port m' is adapted to connect the inlet conduit Q with the discharge conduit Q' which leads to the point to be lubricated. With this construction one reciprocation of the piston will draw oil from the reservoir 40 and discharge it through the sight-feed or "bleed" back into the reservoir; while the next reciprocation of the same piston will draw oil through the inlet conduit Q and discharge it through the discharge pipe Q' to the 45 point to be lubricated. As thus constructed it is obvious that with a single pump I ac-

complish the same result as accomplished with the two pumps of the construction shown in Figs. 1, 2, 3 and 4, and yet for each revolution of the valve shaft in both cases I 50 obtain a discharge of the desired quantity of oil to the point to be lubricated, and also a discharge through the "bleed" or sight feed back to the reservoir of the same quantity of oil, so that the operator may be as- 55 sured how much oil is being delivered for lubrication.

What I claim is,—

1. The combination with a reservoir of a pumping device, two inlet and two discharge 60 conduits therefrom, one discharge conduit leading to a sight feed or bleed and back to the reservoir, the other discharge leading to the point to be lubricated, and a single regulating device for regulating the amount 65 pumped through both discharge conduits.

2. The combination with an oil reservoir, of a pumping device for delivering oil therefrom and feeding it back to the reservoir, and for taking oil from the reservoir and deliver- 70 ing it to the point to be lubricated, an adjusting device for simultaneously regulating the amount of oil pumped through both discharge conduits, and a sight feed or inspection means in the connection between the 75 pumping device and the reservoir.

3. In a force feed lubricator, the combination of a reservoir, two pumps having connected pistons, a single means for adjusting the travel of both pistons, a discharge conduit from one pump leading therefrom and discharging back into the reservoir, a sight feed or bleed therein, and a discharge conduit from the other pump leading to the point to be lubricated. 80

In testimony whereof I affix my signature in presence of two witnesses.

CLARENCE B. HODGES.
